UNITED STATES PATENT OFFICE.

EDWARD W. ROBINSON, OF SAVANNAH, GEORGIA, ASSIGNOR TO INTERNATIONAL BARREL COMPANY, OF SAVANNAH, GEORGIA, A CORPORATION OF GEORGIA.

BARREL.

1,182,422.

Specification of Letters Patent.

Patented May 9, 1916.

Application filed March 1, 1915. Serial No. 11,186.

To all whom it may concern:

Be it known that I, EDWARD W. ROBINSON, a citizen of the United States, residing in Savannah, Georgia, have invented certain 5 Improvements in Barrels, of which the following is a specification.

One object of my invention is to produce from a straight strip of sheet metal a transversely split end hoop for a barrel, keg, 10 cask, or the like (hereinafter, for convenience, termed a "barrel") and another object is to firmly secure such hoop upon the stave ends and head of the barrel. These 15 objects I attain in the manner hereinafter set forth, reference being had to the accompanying drawings, in which—

Figure 1 is a perspective view of the straight strip from which the hoop is to be produced; Fig. 2 is a perspective view of 20 the same after it has been bent into split ring form; Fig. 3 is a perspective view of the split hoop after the further bending of the same; Fig. 4 is a sectional view, on a larger scale, of the end of a headed barrel 25 with the finished hoop applied thereto; Fig. 5 is an end view of the hooped barrel shown in Fig. 4, and Fig. 6 is a transverse section, on a still larger scale, on the line *a—a*, Fig. 5.

30 The blank from which the hoop is to be made is shown in Fig. 1 and consists of a straight strip 1 having flanges 2 and 3 at a right angle to one another. The first step in the production from this strip of the end 35 hoop for the barrel is to bend the same into split ring form, the flange 2 being bent flatwise and the flange 3 edgewise, as shown in Fig. 2, the flatwise bending of the flange 2 causing no change in the character of the 40 same other than the change from the straight to the curved form, but the edgewise bending of the flange 3 causing the same to become wrinkled or corrugated, the depth of the corrugations increasing from 45 its point of junction with the flange 2 to the free edge of the flange because of the contraction in diameter of the free edge of the flange as the same is bent from the straight to the curved form. The flange 3 50 is then again bent downwardly at *x* and inwardly at *y* (Fig. 3) so that the finished hoop presents four members 4, 5, 6 and 7, the member 4 being adapted to bear against the ends of the staves, the members 5 and 6

being substantially parallel with one another and projecting downwardly from the member 4 so as to bear, respectively, against the inner and outer sides of the staves at the end of the barrel, and the member 7 projecting inwardly from the member 6 so as to bear against the head of the barrel, as shown in Fig. 4. In bending the flange downward from *x* to *y* the wrinkles originally formed in that portion of the flange 3 between the line *x* and the inner edge of the flange are 65 partially straightened out again, owing to the increase in the diameter of this portion of the strip which is thereby effected, the wrinkling at the line *y* being practically to the same extent as at the line *x* but increasing from the line *y* to the inner edge of the flange 7. The final bending of the hoop is 70 preferably effected by means of an appropriate press which also has the effect of flattening, in a measure, the wrinkles or corrugations originally formed in the flange 3 by the bending of the same into ring form. 75

By preference, the split hoop is contracted slightly in applying it to the barrel so that its ends will overlap, as shown in Figs. 4, 80 5 and 6.

My improved end hoop, although applicable to barrels generally having sunken heads, is intended especially for use in connection with a wire bound barrel in which 85 the head *a* is supported by the innermost wire *b* of the end pair of stave binding wires, the outer flange 5 of the end hoop both in the single and lapped portions of the same being crimped around the outer 90 wire *c* of said end pair of wires, as shown in Figs. 4 and 6.

In order to prevent loosening of the hoop after it has been applied to the barrel the lapping portions of the hoop are secured together in any suitable way, preferably by driving a staple *d* into the head *a* through the lapped portions of the flange 7, as shown in Fig. 6, and by driving a staple *f* into a stave through the lapped portions of the 100 flange 5 where the same are crimped around the outer wire *c*, as also shown in Fig. 6, although either of these methods of fastening may be employed to the exclusion of the other, if desired.

105 The sheet metal of which the end hoop is composed is of practically uniform thickness and strength throughout, there being

no thinning of the metal of the flange, 5 at and near its free edge as when said flange is expanded at and near said free edge by bending the same edgewise into ring form.

5 I claim:

1. A transversely split end hoop for a barrel, said hoop comprising an annular flange for bearing against the ends of the staves, and a depending flange for bearing against 10 the inner sides of the staves adjacent to their ends, said end-bearing flange having wrinkles or corrugations which gradually increase in size from the outer to the inner portion of said end bearing flange and are 15 continued throughout the depending flange.

2. A transversely split end hoop for a barrel having a sunken head, said hoop comprising an annular flange for bearing against the ends of the staves, a flange depending 20 therefrom for bearing against the inner sides of the staves adjacent to their ends, and a flange projecting inwardly from said depending flange and adapted to bear against the sunken head of the barrel, said end 25 bearing flange having wrinkles or corrugations which gradually increase in size from the outer to the inner portion of said end bearing flange, are continued throughout the depending flange, and gradually increase in 30 size from the outer to the inner portion of the inwardly projecting flange.

3. A transversely split end hoop for a barrel, said hoop presenting an annular flange for bearing against the ends of the 135 staves, and outer and inner depending flanges for bearing, respectively, against the outer and inner sides of the staves adjacent to their ends, said outer flange being flat, and said end bearing flange and inner depending flange having wrinkles or corrugations which gradually increase in size from the outer to the inner portion of the end bearing flange, and are continued throughout the inner depending flange.

4. A transversely split end hoop for a barrel having a sunken head, said hoop presenting an annular flange for bearing against the ends of the staves, and outer and inner depending flanges for bearing, respectively, against the outer and inner sides of the staves adjacent to their ends, and said inner depending flange having a flange projecting inwardly therefrom and adapted to bear upon the sunken head of the barrel, said outer flange being flat, and said end bearing, inner depending and inwardly projecting flanges having wrinkles or corrugations which gradually increase in size from the outer to the inner portion of the end bearing flange, are continued throughout the inner depending flange, and gradually increase in size from the outer to the inner portion of the inwardly projecting flange.

5. A transversely split end hoop for a barrel, said hoop comprising an annular flange

for bearing against the ends of the staves, and a depending flange for bearing against the inner sides of the staves adjacent to their ends, said flanges having wrinkles or corrugations which gradually increases in size from the outer to the inner portion of the end bearing flange and are continued throughout the depending flange, and the flanges at one end of the hoop overlapping the corresponding flanges at the other end of the same.

6. A transversely split end hoop for a barrel having a sunken head, said hoop comprising an annular flange for bearing against the ends of the staves, a flange depending 80 therefrom for bearing against the inner sides of the staves adjacent to their ends, and a flange projecting inwardly from said depending flange and adapted to bear against the sunken head of the barrel, said end-bearing flange having wrinkles or corrugations which gradually increase in size from the outer to the inner portion of said end bearing flange, are continued throughout the depending flange, and gradually increase 85 in size from the outer to the inner portion of the inwardly projecting flange, and the flanges at one end of the hoop overlapping the corresponding flanges at the other end of the same.

7. A transversely split end hoop for a barrel, said hoop presenting an annular flange for bearing against the ends of the staves, and outer and inner depending flanges for bearing, respectively, against 10 the outer and inner sides of the staves adjacent to their ends, said outer flange being flat, and said end bearing flange and inner depending flange having wrinkles or corrugations which gradually increase in size 10 from the outer to the inner portion of the end bearing flange, and are continued throughout the inner depending flange, and the flanges at one end of the hoop overlapping the corresponding flanges at the other 11 end of the same.

8. A transversely split end hoop for a barrel having a sunken head, said hoop presenting an annular flange for bearing against the ends of the staves, and outer and inner depending flanges for bearing, respectively, against the outer and inner sides of the staves adjacent to their ends, and said inner depending flange having a flange projecting inwardly therefrom and adapted to bear upon the sunken head of the barrel, said outer flange being flat, and said end bearing, inner depending and inwardly projecting flanges having wrinkles or corrugations which gradually increase in size from the outer to the inner portion of the end bearing flange, are continued throughout the inner depending flange, and gradually increase in size from the outer to the inner portion of the inwardly projecting flange, and the 12

flanges at one end of the hoop overlapping the corresponding flanges at the other end of the same.

9. A transversely split end hoop for a barrel, said hoop being of substantially uniform thickness throughout, and presenting a flat outside bearing flange, and end and inside bearing flanges having wrinkles or corrugations which gradually increase in size from the outer to the inner portion of the end flange and are continued throughout the inside flange.
10. A transversely split end hoop for a

barrel, said hoop being of substantially uniform thickness throughout, and presenting a flat outside bearing flange, and wrinkled or corrugated end and inside bearing flanges, the latter having a wrinkled or corrugated laterally projecting edge flange.

In testimony whereof, I have signed my name to this specification, in the presence of two subscribing witnesses.

EDWARD W. ROBINSON.
